ALBERT KAZENMAYER AND LOUIS VALOIS, OF NEWARK, NEW JERSEY.

Letters Patent No. 74,375, dated February 11, 1868.

IMPROVED BURGLAR-ALARM.

The Schedule referred to in these Letters Patent and making part of the same.

TO ALL WHOM IT MAY CONCERN:

Be it known that we, LOUIS VALOIS and ALBERT KAZENMAYER, of Newark, in the county of Essex, and State of New Jersey, have invented a new and improved Burglar-Alarm; and we do hereby declare that the following is a full and exact description of the same, reference being had to the accompanying drawings, and to the letters of reference marked thereon.

By reference to the drawings, it will be seen that A is a bolt, to be operated by the spiral spring B, and slides in the studs C D, which studs are fastened to the plate E; and, when in use, the plate is secured to the door-casing F, near to the edge of the door G. H is a lever, hinged at I, and, when the alarm is not set for use, is thrown back against the casing. In that event, the bolt drops down upon the cover K of the torpedo or percussion-box L; but, when set for use, the lever is swung round under the bolt to prop it up, and the cover is slipped off the box.

The lever resting on the shoulder m, when the alarm is set, the end of it passes by the edge of the door, the opening of which pushes the lever from under the bolt, which, by the spring, is projected down into the box upon the percussion or torpedo, and the explosion sounds an alarm.

This becomes a simple and very efficient alarm, as the door cannot be opened without the explosion.

We do not claim the principle of an explosion on the opening of a door, as it is not new; but

What we claim as our invention, and desire to secure by Letters Patent, is—

The combination of the box L with its hinged cover K, and the lever H with bolt A and spring, all as and for the purpose specified.

ALBERT KAZENMAYER,
LOUIS VALOIS.
